THREAD-STAND FOR SEWING MACHINES

Charles R. Odermann, Milford, Conn., assignor to The Singer Manufacturing Company, Elizabeth, N. J., a corporation of New Jersey

Application January 30, 1953, Serial No. 334,201

1 Claim. (Cl. 242—131)

The present invention relates to sewing machines and has for a primary object to provide a new and improved thread-stand for a multi-needle sewing machine.

More specifically it is an object of the present invention to provide a thread-stand adapted to support a plurality of thread supplies for a multi-needle sewing machine in a novel manner such that the thread handling is greatly improved, and particularly such that the likelihood of thread entanglement is greatly reduced over prior devices.

In addition to providing a more efficient thread-handling device, it is a further object of the present invention to provide a thread-stand which is durable, relatively inexpensive to manufacture and otherwise more economical and satisfactory to use.

Having in mind the above and other objects that will be evident from an understanding of this disclosure, the invention comprises the devices, combinations and arrangements of parts as illustrated in the presently preferred embodiment of the invention, which is hereinafter set forth in such detail as to enable those skilled in the art readily to understand the function, operation, construction and advantages of it when read in conjunction with the accompanying drawings in which:

Fig. 1 is a top plan view of a thread-guiding element of a thread-stand made in accordance with the present invention.

Fig. 2 is a perspective view of a thread-stand made in accordance with the present invention and illustrated in use with a sewing machine, fragmentary portions of which machine are included.

Fig. 3 is a detail sectional view taken substantially on the line 3—3 of Fig. 1.

In the drawings there is shown a portion of a sewing machine 1 mounted upon a table or support 2. The machine 1 is of the two-thread chain-stitch multi-needle type and the particular machine selected to illustrate the invention is of the four-needle type which would require four needle threads 3, 4, 5 and 6 and four looper threads 7, 8, 9 and 10. The various threads are each led from a source of supply toward the stitching mechanisms through appropriate well-known thread handling devices such as the tensions 11 which cooperate with the needle-threads 3, 4, 5 and 6, and the thread-guide 12 and thread-tubes 13 which cooperate with the looper threads 7, 8, 9 and 10. It will be understood that the needle-threads and the looper-threads are each supplied from a separate thread-stand which may be substantially identical in construction. The thread-stand for the looper-threads which, as illustrated, embodies the present invention, is herein-after described in detail.

The thread-stand for the looper-threads 7, 8, 9 and 10 comprises a vertical rod 14 preferably formed of a lower section 14a and a smaller diameter upper section 14b releasably secured to the lower section substantially at the midpoint of the stand, the rod 14 being supported by means of a socket member 15 having a flange 16 fastened to the table 2 adjacent the machine 1 as by screws 17,

2

and provided with an upstanding boss 18 having a vertical bore therein in which bore the lower end of the rod 14 is received and in which it is secured as by a set-screw 19. Mounted on the rod 14 at an intermediate point are a pair of similar spool platforms 20 and 21 each adapted to be individually and centrally secured to the rod 14 in any suitable manner. The platforms 20 and 21 are each adapted to support two thread spools or cones 22, one upon each side of the rod 14 and the two platforms are arranged at a right angle to each other whereby the four thread cones 22 will be equally spaced angularly about and radially from the rod 14. Each of the thread cones 22 supplies one of the looper-threads 7, 8, 9 and 10.

Mounted upon the upper end of the rod 14 is a thread-guide, generally designated by the numeral 23 which thread-guide 23 comprises a ring 24 formed of a strip of heavy-gauge sheet metal bent into circular shape. The ring 24 is of such diameter as to overhang substantially the centers of the thread cones 22 and is provided with similar grommets or thread-eyes 25, 26, 27 and 28, each directly above the center of one of the thread cones 22 and adapted to receive the looper-threads 7, 8, 9 and 10 respectively. It will, of course, be understood that thread-apertures would suffice even though the disclosed thread-eyes are deemed preferable. As illustrated in Fig. 3, the thread-eyes comprise a shank portion 29 with a head 30 at one end and a reduced neck portion 31 at the other end. The shank portion 29 is inserted through an appropriate sized aperture in the ring 24 until the shoulder between the shank 29 and head 30 contacts the side of the ring, and a spring-like wire clip 32 is placed over the exposed end of the shank and sprung into the reduced neck 31 to hold the thread-eye on the ring 24.

The ring 24 is secured to the rod 14 by two opposed diametrically arranged bars 33 of sheet metal having the ends 34 and 35 thereof bent to the curvature of the ring 24, which ends 34 and 35 are adapted to be secured to the ring as by bolts 36 and 36' passing through the ends and the ring and receiving nuts 37 and 38 respectively upon the threaded ends thereof. The bars 33 are spaced from each other a distance less than the diameter of the rod 14 and the center portions thereof are arched as at 39 to pass on either side of the rod 14. Screws 40 are passed through the bars 33 on either side of the arched portions 39 and receive the nuts 41 to secure the bars together and to clamp the arched portions 39 against the rod 14.

A second thread guide 42 also formed of a strip of sheet metal is secured to and in the plane of the ring 24 by the bolts 36 and nuts 37 that fasten a central portion 43 of the guide to the ring, which portion 43 is formed to the curvature of the ring. It should also be noted that the portion 43 of the guide 42, together with the bolts 36, serve to hold the free ends of the ring 24 in the desired position. Intermediate portions 43' are provided on either side of the central portion 43, which portions 43' are bent outwardly with respect to the ring 24 and carry guide end portions 44 bent at an angle thereto. The end portions 44 of the guide 42 are thus formed to lie in the plane of said ring and parallel to but spaced from a line tangential to the ring 24 at the center point of the guide, and are provided with thread-eyes 45, 46, 47 and 48, similar to the thread-eyes 25, 26, 27 and 28, each adapted to receive one of the looper-threads 7, 8, 9 and 10, respectively.

A third thread-guide 49 is provided at a level between the guide 42 and the platforms 20 and 21, which guide is carried by an arm 50 that includes a strap-like end 51 adapted to encircle the rod 14 and be clamped thereto by a screw 52. The thread-guide 49 has one leg of a bracket 53 secured centrally thereto as by welding, and the other leg of the bracket 53 is bolted to the arm 50. The thread-guide 49 is arranged parallel to the ends 44 of the guide

42 and along its length is provided with thread-guiding apertures 54, 55, 56 and 57, which are adapted to receive the looper-threads 7, 8, 9 and 10 respectively.

In use, the threads 7 and 10 are led upwardly from the respective cones 22, outwardly from the center of the ring 24 through the thread eyes 25 and 28, respectively, through the thread-eyes 45 and 48 and apertures 54 and 57, respectively, to the guide 12, and through two of the tubes 13 to the looper mechanism. The threads 8 and 9 are led upwardly from the respective cones 22, inwardly toward the center of the ring 24 through the thread-eyes 26 and 27, respectively, over the upper edge of the ring 24, through the thread-eyes 46 and 47 and apertures 55 and 56, respectively, to the guide 12 and through two of the tubes 13 to the looper mechanism. It will be seen that with the above arrangement, the possibility of the threads becoming entangled has been substantially eliminated and that the drag imposed upon the thread as it is drawn through the system has been reduced to a minimum. In addition, it will be seen that the guide 23 can be adjusted vertically with respect to the rod 14 to obtain the optimum thread leads, i. e., to provide a longer pull-off lead from larger thread cones which thus reduces the drag upon the thread, and to provide a shorter pull-off lead for smaller thread cones which thus reduces the length of free travel of the thread leads.

Numerous alterations of the structure herein disclosed will suggest themselves to those skilled in the art. However, it is to be understood that the present disclosure relates to a preferred embodiment of my invention which is for purposes of illustration only and not to be construed as a limitation of the invention. All such modifications which do not depart from the spirit of the invention are intended to be included within the scope of the appended claim.

Having thus set forth the nature of the invention, what I claim herein is:

A thread-stand for use with a sewing machine comprising a rod, an annular ring-like thread-guide formed from a strip of sheet metal bent into substantially cylind-

rical shape and having abutting ends, means for securing said thread-guide concentrically and adjustably to said rod substantially normal thereto, said means comprising two opposed resilient bars passing upon opposite sides of said rod and having complementary rod engaging portions normally spaced from each other a distance less than the diameter of said rod, said bars having the ends thereof bent laterally and arranged in engagement with the inner surface of said thread-guide, one of the ends of each of said bars being in engagement with one of the abutting ends of said thread-guide, means for fastening the ends of said bars to said thread-guide at the points of engagement, means for clamping said bars against said rod, said thread-guide having a plurality of thread-guiding apertures therein arranged with the axes thereof in a plane substantially normal to said rod, a second thread-guide formed of a strip of sheet metal and having a plurality of thread-guiding apertures equal in number to the number of thread-guiding apertures in said first-mentioned thread-guide, said second thread-guide being arranged adjacent the abutting ends of said first-mentioned thread-guide and being secured thereto by said means for fastening the adjacent ends of the bars to said first-mentioned thread-guide, whereby said second thread-guide will span the distance between said abutting ends and will hold the same in abutting relation.
